BUTTON SEWING MACHINE

Joseph H. Pikul, Boston, Mass., assignor to The
Reece Button Hole Machine Company, Boston,
Mass., a corporation of Maine

Application February 19, 1936, Serial No. 64,693

15 Claims. (Cl. 112—111)

This invention relates to machines for sewing on buttons, especially substantially flat buttons having one or more pairs of perforations or holes through which the attaching thread is passed.

5 The invention has for its general object to provide improved stitch-forming mechanism suitable for use in machines of this type and capable of forming a group or predetermined number of attaching stitches alternately through two holes of 10 a pair and thereafter completing the operation by the formation of a tying stitch whereby the attaching stitches are secured against unraveling.

The more particular objects of the invention, together with means whereby the latter may be 15 carried into effect, will best be understood from the following description of an illustrative embodiment thereof shown in the accompanying drawings, the particular mechanism described and shown having, however, been chosen for purposes of exemplification merely, as it will be obvious to those skilled in the art that the invention, as defined by the claims hereunto appended, may be otherwise embodied without departure from the spirit and scope thereof.

25 In said drawings:

Fig. 1 is a side elevation, partly broken away, of the complete machine.

Figs. 2 and 3 are detail views illustrating the attachment of two different types of buttons.

30 Fig. 4 is a horizontal section taken substantially on the line 4—4, Fig. 1.

Fig. 5 is a detail section on the line 5—5, Fig. 1.

Fig. 6 is a horizontal section taken substantially on the line 6—6, Fig. 1.

35 Fig. 7 is a detail section taken substantially on the line 7—7, Fig. 1.

Fig. 8 is a front elevation, partly broken away, of the complete machine.

Fig. 9 is a vertical section taken substantially 40 on the line 9—9, Fig. 1.

Fig. 10 is a detail section taken substantially on the line 10—10, Fig. 1.

Fig. 11 is a plan view, and

Fig. 12 a side elevation of the main cam.

45 Figs. 13 and 14 are sections on the lines 13—13 and 14—14, respectively, Fig. 12.

Fig. 15 is a detail view of a portion of the adjusting mechanism for controlling the amplitude of the lateral movements of the stitch-forming instrumentalities in accordance with the spacing 50 of the holes in the button.

Fig. 16 is a detail perspective view of the lower needle bar guide carrier through which the horizontal movements of the needle are effected and 55 controlled.

Fig. 17 is a fragmentary plan view, partly in section, of the mechanism for moving the needle horizontally.

Fig. 18 is a detail perspective view of certain of the elements of the mechanism shown in 5 Fig. 17.

Fig. 19 is a fragmentary detail view, partly in side elevation and partly in section, of the mechanism for controlling the looper mechanism in the formation of the tying stitches.

Fig. 20 is a view of the same mechanism looking from the left in Fig. 19.

Fig. 21 is a detail section taken substantially on the line 21—21, Fig. 20.

Fig. 22 is a detail fragmentary plan view, partly 15 in section, of the parts shown in Fig. 19.

Figs. 23 to 28 are detail views, partly in section and partly in front elevation, of the stitch-forming mechanism, illustrating the operation during the attaching-stitch-forming cycle.

Figs. 29 and 30 are sections taken on the lines 29—29, Fig. 24 and 30—30, Fig. 25, respectively.

Figs. 31 to 36 are views in front elevation, similar to Figs. 23 to 28, respectively, illustrating the operation of the stitch-forming mechanism during the tying-stitch-forming cycle.

Figs. 37 and 38 are horizontal sectional views taken substantially on the lines 37—37, Fig. 32, and 38—38, Fig. 34, respectively.

Fig. 39 is a detail view of the combined loop 30 deflector and thread breaker.

Figs. 40 to 44 are diagrammatic perspective views illustrating the several steps in the formation of the tying stitch.

For convenience the invention is herein shown 35 as applied to a button sewing machine of the character shown and described in application, Serial No. 60,616, filed January 24, 1936, by Franklin A. Reece, in which machine all of the movements necessary to attach either a two-hole 40 or a four-hole button are imparted to the stitch-forming instrumentalities, as distinguished from the work holding instrumentalities.

Referring to Figs. 1, 4, 6, 8 and 9, the frame or casing of the machine comprises a base or bed 45 70 and an overhanging head 71 supported therefrom by an upright housing portion 72 enclosing the principal parts of the operating and controlling devices. For convenience of assembly and repair said frame or casing comprises two separable main sections A' and A2 and several attached minor parts all of which collectively afford the necessary enclosures, supports, bearings, etc., for the various moving parts.

The bed 70 carries a work plate 73 upon which 55

the fabric W to which the buttons are to be attached is supported and against which it is clamped by a presser foot 74 carrying a button clamp 75 for holding the individual buttons and 5 positioning them for the operation of the sewing instrumentalities.

The main driving and controlling instrumentalities include a main power shaft 76 journaled in suitable bearings in the head 71 and to which 10 power may be applied through a belt pulley 77 under the control of automatic stop mechanism hereinafter referred to, a vertical cam shaft 78 journaled in suitable bearings in the housing 72, driven through a worm 25 and worm gear 26 15 from the main shaft 76, and provided with suitable cams for controlling the movements of the several instrumentalities; and a horizontal looper shaft 79 journaled in suitable bearings in the base 70 and operated and controlled from the 20 cam shaft 78.

The stitch-forming instrumentalities include 25 an eye-pointed needle 80 carried by a needle bar 81 mounted for vertical or longitudinal reciprocation in the head 71 and a pair of loopers 82 and 83 on a looper carrier 84 secured to the looper shaft 79 adjacent its forward end. The sewing thread *t* is supplied to the needle 80 from a suitable source, not shown, through a tension device 85 and suitably arranged guides on the head and 30 needle bar and shown, for example, at 86 and 87, under the control of the usual take-up 88 which, in this instance, is operated by a cam 89 upon the shaft 76.

The needle bar 81 is longitudinally reciprocated by a crank pin 90 carried by the cam 89 and connected by suitable linkage 91 with a collar 92 on said needle bar, and is guided adjacent its upper end in a bearing 93 which, as shown, is carried by a flexible metallic disk 94 suitably clamped in a recess 95 in the upper end of the head 71. This mounting of the needle bar guide 93 may be, and as shown is, substantially as more fully shown and described in the Reece Patent No. 1,993,350, March 5, 1935, and is such 45 as to permit the needle bar a limited universal swinging movement about the point of intersection of its axis with the plane of the disk 94. Adjacent its lower end the needle bar is guided in a bearing 96 similarly mounted by means of a disk 97 in a carrier member 98 mounted, as hereinafter described, for movement in a horizontal plane both laterally and longitudinally of the machine frame.

In attaching a two-hole button B, as shown in Fig. 2, the carrier 98 is oscillated laterally between successive descents of the needle 80 to cause said needle to pass alternately through the holes *h* and *h*^x in the button, the looper carrier being at this time oscillated laterally by the shaft 79 to cause the loopers to cooperate with the needle, as hereinafter more fully explained, in the formation of stitches *s* passing through said holes and serving to attach the button to the fabric W. In attaching a four-hole button, such as shown at B' in Fig. 3, the same operations are performed to form a series of attaching stitches *s'* passing through the holes *h*¹ and *h*², after which the carrier 98 is shifted longitudinally, or in a direction fore and aft of the machine, to bring the needle into the plane of the holes *h*³ and *h*⁴ of the other pair, the looper shaft 79 with the looper carrier 84 and loopers 82 and 83 being similarly shifted to maintain the cooperative relationship of said loopers with the needle. 70 Thereafter the sewing operations are repeated to

form a second set of attaching stitches *s*² passing through the holes *h*³ and *h*⁴.

Specifically the presser foot 74 and button clamp 75 carried thereby form no portion of the present invention and may be of any construction and arrangement suitable to perform their intended functions and permit the operation of the stitch-forming instrumentalities as above described. As shown, the presser foot 74 is secured to a short upright rod 100 (see Figs. 1, 7 10 and 8) carried by an arm 101 projecting from a slide 102 guided for vertical movement in the head 71. The slide 102 is normally held downward to urge the presser foot against the work by a spring 103 but may be moved upwardly 15 against the tension of said spring, to raise the presser foot, by a lever 104 connected by a chain 105 with a suitable treadle, not shown.

The carrier member 98 for the lower needle bar guide 96 is guided for longitudinal movement 20 in a groove in the top of a head 106 (Figs. 1, 4, 16 and 17) having a shank or trunnion 107 received in a socket 108 in the bottom wall of the head 71 of the machine, whereby said head 106 is pivoted for oscillation about the axis of said 25 shank. Said carrier is, therefore, free to move longitudinally in the head 106 or to oscillate laterally with said head about the pivotal axis of the latter. Said carrier is further held and guided for movement in a horizontal plane by 30 channel members 109 (Figs. 1 and 10) each secured to bosses 110 on the bottom wall of the head 71 by bolts 111 (see also Fig. 4), said carrier being retained within the groove of said channel by a cover plate 112 secured in place by said 35 bolts 111.

The carrier 98 is oscillated laterally about the axis of the pivot 107 to cause the needle to pass alternately through the holes *h*, *h*^x (Fig. 2), *h*', *h*² (Fig. 3) or *h*³, *h*⁴, by mechanism most clearly 40 shown in Fig. 17. Said mechanism comprises a link 113 having a pin or stud 114 (see also Fig. 9) a downwardly projecting portion of which is received in a longitudinally disposed way 115 (Fig. 16) in the upper face of the carrier 98, and an 45 upwardly projecting portion of which is received in a way 116 in a head 117 having a shank 118 pivoted in a bracket 119 in the head 71. The way 116 permits lateral movement of the stud 114, and consequently lateral oscillation of the carrier, while holding said stud against longitudinal movement in the way 115; while the latter way permits longitudinal movement of the carrier 98 50 independently of said stud as hereinafter explained. The opposite end of the link 113 is provided with a stud 120 received in an arcuate groove 121 in one arm of a lever 122 (see Figs. 4 and 9) secured to an upright shaft 123 journaled in a bearing 124 depending from the top of the head 71. At its opposite end the lever 122 carries a pin 125 which engages a cam groove 127 in the upper face of a main cam 129 fast on the vertical cam shaft 78. With this construction it will be seen that rotation of the cam 129 will cause the lever 122 to swing about the axis of 60 the shaft 123, and that this movement will be transmitted from said lever to the carrier 98 through the link 113.

The amplitude of the lateral vibration thus imparted to the carrier 98 will depend upon the 70 point of engagement of the stud 120 with the groove 121, and in order to permit this to be readily adjusted in accordance with the lateral spacing of the holes in the button, the link 113 is provided with a third stud 130 engaged by a fork 75

131 (see also Figs. 4, 5, 9 and 15) carried by a slide 132 guided for horizontal movement on the side wall of the head 11 by a stud 133 projecting inwardly from said wall and engaging a slot 134 5 in the slide and a clamp screw 135 projecting through a slot 136 in the wall and in threaded engagement with said slide. By loosening the clamp screw the slide 132 may be moved longitudinally, and by tightening said clamp screw it 10 may be secured in adjusted position.

The mechanism for moving the carrier 98 longitudinally is likewise shown in Fig. 17 and comprises a link 146 having at its forward end a stud 147 received in a transverse groove or way 148 15 in the upper face of the carrier 98 adjacent its rear end. This construction permits the carrier to be swung laterally by the link 113, as above described, independently of the link 146 and stud 147. The stud 147 also pivotally connects the link 20 146 with an arm 149 on a vertical rock shaft 150 journaled in suitable bearings on the interior of the main casing, said connection serving to retain the stud 147 in the groove 148. At its rear end the link 146 carries a stud 151 which engages 25 a groove 152 in an arm 153 secured to a second vertical rock shaft 154. Adjacent its lower end the rock shaft 154 has secured thereto an arm 155 having a bifurcated end between the branches of which is pivoted the end of a link 156 having 30 a slot 157 (Fig. 18) to receive a stud 158 (Fig. 17) depending from a bracket or interior frame member 159 within the main casing and the form of which is most clearly shown in Fig. 9. The link 156 is, therefore, guided on the stud 158 by engagement of the latter with the slot 157 and is 35 supported by a flange or head 160 (Fig. 9) on the lower end of the stud. The link 156 has secured thereto a pair of contact or cam-follower blocks 161 embracing between them and cooperating 40 with an edge cam 162 rotatably mounted on the stud 158 and the hub of which is provided with a spur gear 163 meshing with a pinion 164 on the lower end of the main cam shaft 78. The gear 163 and pinion 164 are of such sizes as to 45 constitute two to one gearing between the cam 162 and the cam shaft 78, so that the cam 162 is rotated at one half the speed of the main cam 129. Accordingly, after one complete rotation of the cam 129 to cause the cam groove 127 thereof to 50 produce a predetermined number of lateral reciprocations of the needle bar to form, for example, the group of stitches s' (Fig. 3), the cam 162 will cause the carrier 98 and needle bar to be shifted longitudinally of the machine in one 55 direction, after which a second rotation of the cam 129 will cause the necessary number of lateral reciprocations to form the group of stitches s², whereupon the cam 162 will return the carrier and needle bar to their original longitudinal 60 positions. The amplitude of the longitudinal or fore and aft movement of the carrier 98 and needle bar 81 is determined by the position of the stud 151 in the groove 152 of the arm 153, and means are preferably provided whereby this may 65 be conveniently adjusted in accordance with the fore and aft spacing of the holes h¹, h², and h³, h⁴. Such means, however, form no portion of the present invention and therefore need not be described in detail herein.

70 The looper shaft 79 is slidably mounted at its rear end in a sleeve 179 (see Fig. 6) rotatably mounted in a suitable bearing in the frame member 159. Adjacent the forward end of the sleeve 179 the shaft 79 has secured thereto a collar 180, 75 and the contiguous ends of said sleeve and collar

are suitably formed to constitute the complementary elements of a slip coupling or clutch connecting the sleeve and shaft for oscillation in unison while permitting longitudinal movement of the shaft relative to the sleeve. At its rear 5 end the sleeve 179 is formed with a head 181 (Figs. 6 and 19) having a transverse bore in which a stud 183 (Figs. 1 and 19) is rotatably and slidably mounted. The stud 183 is provided with a head 184 having a transverse bore in which is slidably 10 and rotatably received a stud 185 projecting longitudinally from the end of an arm 186 secured to one end of a transverse rock shaft 187 journaled in a suitable bearing in the frame member 159. By this construction the shaft 187 and 15 sleeve 179, although disposed perpendicular to one another, are connected for oscillation in unison. At its opposite end the rock shaft 187 has secured thereto a bifurcated arm 188 between the bifurcations of which is pivoted at 189 the lower 20 end of a link 190. The upper end of the link 190 is provided with a transverse stud 191 the inwardly projecting end of which is received in an arcuate groove 192 in one end of a lever 193 fulcrumed at its opposite end on a stud 194 projecting inwardly from the side wall of the housing 72. Intermediate its ends the lever 193 carries a pin 195 which engages a cam groove 197 formed in the side or periphery of the main cam 129. The groove 197 corresponds to the groove 127, that 30 is to say, the number and timing of the oscillations of the looper shaft 79 produced by the former correspond to the number and timing of the lateral oscillations of the needle produced by the latter. Accordingly, the oscillations of the 35 loopers are synchronized with the lateral oscillations of the needle, and it is obvious that the amplitude of the former must vary with the amplitude of the latter. The amplitude of oscillation of the looper shaft 79 depends upon 40 the position of the stud 191 in the groove 192 of the lever 193, and in order that this position may be suitably adjusted concurrently with the adjustment of the position of the stud 120 in the groove 121 of the lever 122 the slide 132 (Fig. 15) 45 by which the latter stud is adjusted is provided with a depending flange 202 having a slot 203 to receive the outwardly projecting end of the pin 191 (see also Fig. 1). Consequently, when the slide 132 is adjusted in accordance with the lateral spacing of the holes in the button, the studs 120 and 191 will be simultaneously adjusted to 50 control both the lateral throw of the needle and the amplitude of vibration of the loopers, thereby maintaining the proper relation between the 55 movements of said parts.

When the needle bar carrier 98 is shifted longitudinally, or in a direction fore and aft of the machine, in sewing a four-hole button, in order to transfer the operation of the needle from the 60 plane of one pair of holes, for example, the holes h¹, h², to the plane of another pair, for example, the holes h³, h⁴, the looper shaft 79 must be likewise shifted longitudinally to maintain the proper cooperative relationship of the loopers to the needle, and to this end, in the construction shown, the following means are provided, reference being had to Figs. 1, 6 and 9. The vertical rock shaft 150, whose arm 149 is connected with the link 146 by the stud 147, has secured to its lower end 70 a second arm 204 connected by a link 205 with a fork 206 through openings in the arms of which the looper shaft 79 extends, and whose arms embrace a collar 207 secured to said looper shaft, whereby, when the carrier 98 is shifted longitudi- 75

nally by the lever 153 acting through the link 146, the shaft 79 will be correspondingly shifted longitudinally. It will be noted that the length of the arm 204 is greater than that of the arm 149 5 to compensate for the difference in distance, from the pivotal center of the needle bar guide 93, of the shaft 79 and needle bar carrier 98, respectively.

As above stated, the main cam 129 makes one 10 complete rotation for each group of stitches s , s^2 or s^3 , and the number of stitches of each group depends upon the shape of the cam grooves 127 and 197. Referring to Fig. 11, the cam groove 127 is formed with five radially offset portions, 15 adapted to produce five complete lateral reciprocations of the needle, in synchronism with the vertical reciprocations thereof, and with a concentric portion 231 during which the needle is caused to make two descents through the same 20 hole in the button in order to form a knot or tying stitch, as hereinafter further explained, it being understood that the groove 197 is correspondingly formed to produce the requisite cooperative oscillatory movements of the looper. Consequently, 25 each group of stitches will comprise ten attaching stitches and a tying stitch, the whole group requiring twelve vertical reciprocations of the needle.

The belt pulley 77 (Fig. 1) is loose on the shaft 30 76 and is adapted to be clutched thereto by a combined clutch and stop mechanism which may be substantially similar to those shown and described in the patents to Mello, No. 1,227,643, May 29, 1917, and Reece, No. 1,730,014, October 35 1, 1929. As more fully explained in application Serial No. 60,616, above referred to, this mechanism is operated by a stud 301 (Figs. 11 to 14) on the main cam 129 through connections adjustable to cause stopping of the machine after one complete rotation of said cam, as in sewing one group 40 of stitches through the holes of a two hole button, or after more than one such rotation, as in sewing groups of stitches through the pairs of holes of a four hole button, or in sewing a plurality of groups through the same pair of holes of a two hole button. These connections constitute no portion of the present invention and therefore do not require description in detail herein.

Referring particularly to Figs. 23 to 30, the 50 loopers 82 and 83 are formed with thread engaging shoulders z and are secured in fixed position on the looper carrier 84 which also carries a pair of loop spreaders 223 and 224 corresponding respectively to the loopers 82 and 83. The 55 loop spreaders 223 and 224 are pivotally mounted in the carrier 84 by means of shanks 225 rotatably mounted in said carrier and are normally held with their ends closely adjacent the ends of the loopers and in substantially the same vertical plane therewith, as shown in Fig. 29, by means of torsion springs 226 interposed between said carrier and tail portions 230 of said loop spreaders, the positions of said loop spreaders under the influence of said springs being determined by 60 angularly adjustable stops 227. Said loop spreaders are moved out of the latter positions to spread the thread loops by means of a cam plate 228 which, during the attaching-stitch-forming cycle, is held stationary, as hereinafter more fully explained, but which is formed with bevelled edges 229 adapted, as the looper carrier is oscillated, to engage the tail portion 230 of one or the other of the loop spreaders and move the same into loop spreading position, as shown in the 65 case of the loop spreader 223 in Fig. 30.

The operation of the above mechanism in the formation of the attaching stitches s is illustrated, in the case of a two-hole button B, in Figs. 23 to 30. As above explained the needle 80 is vibrated laterally between successive descents, 5 causing the same to pass alternately through the holes h and h^x in the button, by the cam groove 127 in the cam 129, the looper shaft 79 and looper carrier 84 being oscillated in synchronism with the operations of the needle by the cam 10 groove 197. At the beginning of the attaching operation, the needle descends through one of said holes, for example the hole h shown at the left in Fig. 23 and through the work W, the looper carrier at this time moving toward the right 15 from its extreme position toward the left. The needle then rises, leaving behind it a thread loop l , as shown in Fig. 24. The looper carrier continues its movement toward the right, causing the end of the looper 82, as well as the end of 20 corresponding loop spreader 223 (which at that time is immediately above said looper, as shown in Fig. 29) to enter said loop. The needle continues to rise, and the looper carrier continues to move toward the right, causing the loop l to 25 be caught by the shoulder z of the looper 82 and carried into a position below the hole h^x . During this movement the tail 230 of the loop spreader 223 engages the left bevelled edge 229 of the cam plate 228, causing said spreader to be rocked 30 about its pivot 225 and carrying its end away from the looper 82, thereby spreading said loop, as shown in Fig. 30. The needle 80 is then moved laterally toward the right and again descends, this time passing through the holes h^x , and in its 35 descent passes through the spread loop l , the looper carrier simultaneously moving toward the left to release said loop which is accordingly cast about the needle as shown in Fig. 26, and drawn up to the work by the takeup 88. The needle then 40 rises, leaving behind it a second loop l' which, as the looper carrier 84 continues its movement toward the left, is immediately entered by the looper 83 and loop spreader 224, in a manner similar to the engagement of the loop l by the looper 45 82 and spreader 223 as above explained. Continued movement of the looper carrier into its extreme position toward the left causes the loop l' to be spread by the spreader 224 and caught by the shoulder z of the looper 83 so as to be 50 carried into and held in a position for the needle 80 to pass therethrough during its next descent through the hole h , thereby completing the first 55 stitch. These operations are continued to form a group of attaching stitches s of a number determined by the shape of the cam grooves 127 and 197.

At the completion of the group of attaching stitches, the needle is caused to descend twice through the same hole in the button, due to the 60 concentric portion 231 of the groove 127, during which the looper mechanism, together with certain associated parts about to be described, operate in such a manner as to form a tying stitch or knot which will prevent unraveling of the attaching stitches.

Referring to Figs. 19 to 22, and particularly to Fig. 21, the cam plate 228 is secured, as by riveting, to a hub 232 mounted to turn on a reduced end portion 233 of the looper shaft 79, while the 70 looper carrier 84 has a hub portion 234 secured, as by pins 235, to said reduced portion. The cam plate 228, while free to turn on the shaft, is held against movement longitudinally thereof, in one direction by engagement of said cam plate with 75

the looper carrier 84, and in the opposite direction by engagement of the end of the hub 232 with a shoulder 236 at the end of the reduced portion 233. Mounted to turn on the hub 234 of the looper carrier is a loop deflector carrier 237 which is retained on the shaft by a nut 238 and is positioned longitudinally of the shaft between said nut and a spacer sleeve 239 interposed between the same and the body of the looper carrier 84. The cam plate 228 and loop deflector carrier 237 are connected with one another, for turning movement in unison about the axis of the looper shaft, by a pin 240. The pin 240 has a reduced end portion 241 which is received in a slot 242 (Fig. 20) in the loop deflector carrier 237, whereby the relative angular positions of said carrier and the cam plate 228 can be adjusted if necessary, said parts being secured in adjusted position by a nut 243 applied to the threaded end 20 of said reduced portion.

The pin 240 is connected by a link 244 with a pin 245 carried between the ends of a pair of arms 246 (Fig. 19) projecting from a hub 247 secured, as by a pin 248, to a shaft 249 suitably journaled in the frame and extending parallel to the looper shaft 79. The spacing of the arms 246 relative to the width of the link 244 is sufficient to permit the above described longitudinal movement of the looper shaft and the parts carried thereon without corresponding movement of the shaft 249. The shaft 249 is provided adjacent its inner end with a skew gear 250 which meshes with a skew gear 251 on the lower end of an upright shaft 252 suitably journaled in the frame and having secured to its upper end, as by a pin 253, a head 254. The head 254 carries a pin 255 which engages a groove 257 formed in the bottom of the main cam 129.

Secured to the carrier 237 is the shank 267 (see particularly Fig. 39) of a combined loop deflector and thread breaker 268, said shank being of such a shape that, as said carrier is oscillated about the axis of the looper shaft 79, the loop deflector 268 will move in an arcuate path immediately over the loopers and loop spreaders. Said loop deflector is provided at its free end with a needle receiving slot 269 and at the opposite sides of said slot with longitudinal projections terminating in oppositely bevelled end surfaces 270. One of said projections is further provided with a longitudinal extension terminating in a hook 271.

The cam groove 257 (Fig. 13) is for the most part concentric but includes an operative portion 272 so arranged as to be engaged by the pin 255 when the pin 125 is in the concentric portion 231 of the groove 127. The form of the cam groove portion 272 is such as to cause an oscillation of the cam plate 228 and loop deflector carrier 237 in the manner hereinafter described. The cam groove 197 is formed with a portion 273 offset in the same manner as the portions producing the attaching-stitch-forming oscillations of the looper, but to a less extent, so that the movement produced thereby is of less amplitude, and said cam portion includes two stages 274 and 275, the former offset to a greater extent than the latter. The arrangement is such that the pin 195 engages the cam groove portion 273 when the pin 125 is in the concentric portion 231 of the groove 127 and when the pin 255 is in the operative portion 272 of the cam groove 257.

The operation of the parts in the formation of the tying stitch is illustrated in Figs. 31 to 38 and 40 to 44. After the formation of the last 75 loop of the group of attaching stitches, for ex-

ample, the loop l^x formed by the descent of the needle through the hole h^x , the needle again descends through the other hole, for example the hole h shown at the left in Fig. 31, and thereafter rises, leaving behind it a loop l^a as shown in Fig. 5 32. Simultaneously the looper carrier moves toward the right, causing the looper 82 and loop spreader 223 to enter said loop as shown in Figs. 32, 33, 37 and 40, the operations thus far being substantially like those taking place in the formation of the attaching stitches as shown in Figs. 24, 25 and 29 except that the movement of the looper and loop spreader, caused by the cam groove portion 274, is of less amplitude, being only sufficient to carry the loop slightly beyond the center line between holes h and h^x . This movement is insufficient to cause the tail portion 230 of the loop spreader 223 to be operated by the left bevelled edge 229 of the cam plate 228 to a sufficient extent to cause said loop spreader 20 to spread the loop were said cam plate to remain stationary. However, at this time the operative portion 272 of the cam groove 257 causes said cam plate, together with the carrier 237 and loop deflector 268, to be turned in a counter-clockwise 25 direction or toward the left as shown in Figs. 33 and 34. This movement of the cam plate causes the spreader 223 to be operated to spread the loop l^a which is caught by the bevelled ends 270 of the deflector 268 and carried to the left 30 therewith, the looper 82 and spreader 223 continuing to recede or move toward the left during this operation until the parts reach the position shown in Figs. 34, 38 and 41. The needle thereupon again descends through the same hole h , 35 through the loop l^a which is thus held open and in a position to receive it, and through the slot 269 in the loop deflector 268. The movement of the looper 82 and spreader 223 toward the left continues, causing them to release the loop l^a 40 which is thus cast about the needle and drawn up against the work by the takeup, as shown in Figs. 35 and 42. The needle then rises, leaving behind it a loop l^b as shown in said last named figures, whereupon, as the needle continues to 45 rise, the loop deflector, under the influence of the operative portion 272 of the cam groove 157, moves toward the right causing said loop to be caught by the hook portion 271 of the loop deflector, as shown in Figs. 36 and 43. Continued 50 movement of the loop deflector toward the right, in cooperation with the takeup, causes said loop, and consequently the knot formed thereby with the loop l^a to be drawn tight, and thereafter further movement of the loop deflector in the same 55 direction causes the thread constituting said loop l^b to be broken, as shown in Fig. 44, so that the thread t can be withdrawn through the hole h without untying said knot.

I claim:

1. In a machine for sewing on buttons, stitch forming mechanism including a needle, cooperating loop handling elements, means for reciprocating said needle longitudinally, means for vibrating said needle laterally to cause the same to 65 pass alternately through different holes in a button in the formation of attaching stitches and having provision for thereafter causing said needle to pass twice through the same hole to form a tying stitch, and means for operating said loop handling elements and having provision for causing different operations of said elements during the formation of attaching stitches and tying stitches respectively.

2. In a machine for sewing on buttons, stitch 75

forming mechanism including a needle, cooperating loop handling elements including a looper and a loop spreader, means for reciprocating said needle, means for moving said loop handling elements transversely of the needle to cooperate therewith in the formation of attaching stitches and tying stitches, and means for moving said loop spreader relative to said looper to spread the loop, said last named means having a different operation in the formation of attaching stitches and tying stitches, respectively.

3. In a machine for sewing on buttons, stitch-forming mechanism including a needle, means for reciprocating the same, a looper carrier, loopers and loop spreaders carried thereby, means for oscillating said looper carrier in a path transverse to the path of movement of said needle to cause said loopers to cooperate with said needle in the formation of attaching stitches and tying 20 stitches, said oscillating means being adapted to produce a greater amplitude of movement in the formation of attaching stitches than in the formation of tying stitches, a spreader actuator for moving said loop spreaders relative to said loopers to spread the loops, and means for holding said actuator stationary during the formation of attaching stitches and for moving the same relative to said carrier in the formation of tying stitches.

30 4. In a machine for sewing on buttons, stitch-forming mechanism including a needle, means for reciprocating the same longitudinally, means for vibrating it laterally to cause it to pass alternately through different holes in the button in the formation of attaching stitches and having provision for thereafter causing it to pass twice through the same hole to form a tying stitch, loop handling elements, and means for operating said elements to cause the same to present thread loops for the passage of the needle therethrough alternately in different positions in the formation of attaching stitches and for holding a previously formed loop in the path of movement of the needle when the latter passes a second time through the same hole in the formation of the tying stitch.

45 5. In a machine for sewing on buttons, stitch-forming mechanism including a needle, means for reciprocating the same longitudinally, means for vibrating it laterally to cause it to pass alternately through different holes in the button in the formation of attaching stitches and having provision for thereafter causing it to pass twice through the same hole to form a tying stitch, loop elements, means for operating said elements to cause the same to present thread loops for the passage of the needle therethrough alternately in different positions in the formation of attaching stitches, a loop deflector, and means for operating the same to hold a previously formed loop in the path of movement of the needle when the latter passes a second time through the same hole in the formation of the tying stitch.

60 6. In a machine for sewing on buttons, in combination, stitch-forming elements and a co-operating thread handling device, means for operating said stitch-forming elements to form a group of attaching stitches and means for operating said thread handling device to cause the latter to cooperate with said stitch-forming elements to form a tying stitch at the completion of said attaching stitches.

65 7. In a machine for sewing on buttons, a needle, cooperating loop handling means including a pair of loopers, means for causing said needle to pass alternately through different holes in a but-

ton and thereafter to pass twice through the same hole, and means for causing the respective loopers to cooperate alternately with the needle in its alternate passage through different holes to form a group of attaching stitches and thereafter to cause one of said loopers to cooperate with said needle during its passage twice through the same hole to form a tying stitch.

8. In a machine for sewing on buttons, a needle, cooperating loop handling means including a pair of loopers each having associated therewith a coacting loop spreader, means for causing said needle to pass alternately through different holes in a button and thereafter to pass twice through the same hole, and means for causing the respective loopers and loop spreaders to cooperate alternately with the needle in its alternate passage through different holes to form a group of attaching stitches and thereafter to cause one of said loopers and its coacting loop spreader to cooperate with said needle during its passage twice through the same hole to form a tying stitch.

9. In a machine for sewing on buttons, a needle, cooperating looper means, means for causing said needle to pass alternately through different holes in a button and thereafter to pass twice through the same hole, and means for oscillating said looper means through a given range to cooperate with the needle in its alternate passage through different holes to form a group of attaching stitches and thereafter through a different range to cooperate with said needle during its passage twice through the same hole to form a tying stitch.

35 10. In a machine for sewing on buttons, a needle, cooperating loop handling elements, mechanism for operating said needle and loop handling elements to cause the latter to cooperate with the former in the formation of a predetermined number of attaching stitches, and other means for thereafter cooperating with the needle and loop handling elements in the formation of a tying stitch.

11. In a machine for sewing on buttons, a needle, cooperating loop handling elements, mechanism for operating said needle and loop handling elements to cause the latter to cooperate with the former in the formation of a predetermined number of attaching stitches, and a loop deflector for thereafter cooperating with the needle and loop handling elements in the formation of a tying stitch.

45 12. A machine for sewing on buttons, stitch forming mechanism including a needle and co-operating loop handling elements comprising a looper and a loop spreader, means for operating said elements to cause the same to cooperate with the needle in the formation of attaching stitches, a spreader actuator, a loop deflector, and means for actuating said spreader actuator and loop deflector in the formation of a tying stitch.

55 13. A machine for sewing on buttons, stitch forming mechanism including a needle and co-operating loop handling elements comprising a looper and a loop spreader, means for operating said elements to cause the same to cooperate with the needle in the formation of attaching stitches, a spreader actuator, a loop deflector, and common means for actuating said spreader actuator and loop deflector in the formation of a tying stitch.

65 14. In a machine for sewing on buttons, stitch forming mechanism including a needle, means

for reciprocating the same longitudinally, means for vibrating it laterally to cause it to pass alternately through different holes in the button for the formation of attaching stitches and having provision for thereafter causing it to pass twice through the same hole to form a tying stitch, a looper carrier, loopers and loop spreaders carried thereby, means for oscillating said looper carrier in a path transverse to the path of movement of said needle to cause said loopers to cooperate with said needle in the formation of attaching stitches and tying stitches, a spreader actuator for moving said loop spreaders relative to said loopers to spread the loops, a loop deflector, and means for moving said spreader

actuator relative to said carrier and for operating said loop deflector in the formation of tying stitches.

15. In a machine for sewing on buttons, in combination, stitch-forming elements including 5 a needle and cooperating loop handling means, an additional thread handling device, means for operating said stitch-forming elements to form a group of attaching stitches, and means for operating said thread handling device to cause the 10 latter to cooperate with said stitch-forming elements to form a tying stitch at the completion of said attaching stitches.

JOSEPH H. PIKUL.
